United States Patent Office

Des. 177,773
Patented May 22, 1956

177,773

TRUCK

Luther W. Stier, Rochester, and Charles M. Jordan, Birmingham, Mich., assignors to General Motors Corporation, Detroit, Mich., a corporation of Delaware

Application May 26, 1955, Serial No. 36,236

Term of patent 7 years

(Cl. D14—3)

Fig. 1 is a side elevational view of a truck embodying our new design with the side opposite being substantially the same as that shown;

Fig. 2 is a front view thereof; and

Fig. 3 is a rear view thereof.

The dominant features of our design reside in the full line portion of the drawing.

We claim:

The ornamental design for a truck, substantially as shown and described.
